UNITED STATES PATENT OFFICE.

JOHN HOFFER, OF MARIANNA, PENNSYLVANIA.

SAFETY MECHANISM FOR ELEVATORS.

1,396,751.

Specification of Letters Patent. Patented Nov. 15, 1921.

Application filed January 10, 1920. Serial No. 350,558.

To all whom it may concern:

Be it known that I, JOHN HOFFER, residing at Marianna, in the county of Washington and State of Pennsylvania, a subject 5 of the former Kingdom of Hungary, in the former Austro-Hungarian Empire, have invented or discovered certain new and useful Improvements in Safety Mechanism for Elevators, of which improvements the following is a specification.

My invention relates to improvements in safety mechanism applied to elevator cars and cages—such as those used in mines and in office buildings, cars raised and lowered 15 by cable for carrying men and vehicles upon steep hill sides, and the like. The object is to eliminate and overcome a difficulty in the proper operation of mechanisms of this sort which otherwise comes about in service, in 20 consequence of elongation of the car-sustaining cable.

In the accompanying drawings, Figure 1 shows in elevation an elevator installation in which my invention is applied; Fig. 2 is 25 a similar view of one car alone, showing in specific form a detail presently to be described.

Two cars 1, 1 are suspended in their shafts by cables 2, 2, and the cables are, it will be 30 understood, parts of a continuous whole, to the end that the two cars are sustained in counterbalance, one against the other—an arrangement peculiarly useful in mines and upon inclined planes of city transportation, 35 and an arrangement which requires a minimum amount of power to effect elevation.

The safety device is one which is operated by a second cable 9, upon which, on the 40 parting of the car-sustaining cable 2, the weight of the car comes. Thereby the safety device is operated. The invention is not conditioned upon any specific form of safety device; it is requisite to the invention only that the safety device be operable by tension upon a cable; beyond this, the particular construction may be whatever is preferred. In the drawings I have shown the safety device of my now pending application 45 for Letters Patent, Serial No. 286,665, filed April 1, 1919, wherein the tension thrown upon cable 9, when the weight of a car is imposed upon it, turns a drum 8 and turning of the drum is communicated to shafts 11 which in turning cause clamping members 10, arranged in pairs upon opposite sides of posts 3, to come to post-engaging

positions and so to arrest the falling of a car. But it will be understood that the safety device of my Patent No. 1,324,451 might be employed, or any other safety device having the characteristic already defined—that, namely, of operating under tension exerted through a cable.

Ordinarily in an installation which includes two cars hung in counterbalance the cable for operating the safety device extends from one car, over sheaves at the top of the shaft or runway, to the other car; the safety cable so arranged is normally slack. In case the car-sustaining cable breaks, the 70 weight of the car is at once imposed on the safety cable, the safety cable is drawn taut, and the safety device operates, to arrest the car as it begins to fall.

A difficulty lies in this: that, as the elevator continues in use, the car-sustaining cable is liable to stretch, until the slack in the safety-device cable is taken up, and the safety device comes into action inopportunistically.

My invention consists in carrying the cable 9, through which the safety device is operated, from one car upward to the top of the shaft and thence downward to the other car, and in forming in this cable, intermediate its length, a loop 12, depending from the top of the shaft. In this loop I hang a weight 13, and adjacent and above the weight I place a stop 14. The connection of the cable 9 to the safety devices of 90 the two cars is such that the safety devices remain in normal inactive position under the minor tension exerted through the cable 9 by the weight 13, but under the major tension presently to be more fully indicated 95 which, upon parting of cable 2 is exerted through cable 9, the safety devices will come into action and both cars will by their safety devices be secured in the shafts, against the possibility of falling.

One specific way of accomplishing the end just described is shown in Fig. 2. The cable 9 is, at the end where it engages drum 8, slackened by line 15, which hitches cable 9 at a point remote from the drum directly to 105 the car. Line 15 is relatively weak; it is sufficiently strong to sustain weight 13 under all conditions of use, but in case cable 2 parts and one car or both begin to fall, immediately loop 12 in cable 9 will shorten 110 and weight 13 will abut upon stop 14. Thereupon the tension exerted upon lines 15 will

break them both and both the drums 8 of the safety devices will turn, both safety devices will operate and both cars will be secured in whatever position they chance to be found 5 in the shafts. All this will come about before the broken-away car has by falling gained any considerable momentum.

Thus it will be appreciated that cable 9 is held by weight 13 always taut, that loop 10 12 by growing shorter makes compensation for stretching of the car-sustaining cable; the safety device can never be operated by the mere stretching of the car-sustaining cable; but, in case cable 2 breaks, the safety 15 devices will be operated on the engagement of weight 13 with stop 14 by the consequent sudden tension imposed on cable 9.

I claim as my invention:

In a safety device for elevator cars and 20 cages the combination of two cars hung in

counterbalance, a safety cable extending from car to car and hanging intermediate its length in a loop susceptible to elongation and shortening, a tension-operated safety mechanism borne by one of said cars, 25 to which safety mechanism said safety cable is connected, means rendered ineffective under major stress, relieving said safety mechanism under normal conditions of the weight of said looped safety cable, and a 30 stop limiting the extent to which the loop in said safety cable may shorten, substantially as described.

In testimony whereof I have hereunto set my hand.

JOHN HOFFER.
